UNITED STATES PATENT OFFICE

165,555

COMBINED FISHING ROD AND REEL

Arthur C. Shafer, Cincinnati, Ohio

Application January 6, 1949, Serial No. 81

Term of patent 14 years

(Cl. D31—4)

To all whom it may concern:

Be it known that I, Arthur C. Shafer, a citizen of the United States, residing at Cincinnati, in the county of Hamilton and State of Ohio, have invented a new, original, and ornamental Design for a Combined Fishing Rod and Reel, of which the following is a specification, reference being had to the accompanying drawings, forming a part hereof.

In the drawing:

Fig. 1 is a plan view of a combined fishing rod and reel, showing my new design;

Fig. 2 is a side view; and

Fig. 3 is a bottom plan view thereof.

I claim:

The ornamental design for a combined fishing rod and reel, as shown.

ARTHUR C. SHAFER.
